SANDING MACHINE

Jack P. Elliott, Westfield, Pa., assignor to Eberle
Tanning Company, Westfield, Pa., a corpora-
tion of Pennsylvania

Application March 31, 1942, Serial No. 437,070

10 Claims. (Cl. 51—38)

This invention relates to the art of sanding machines, and more particularly to a machine for the sanding of various articles, including pieces of leather.

Prior sanding machines have had to be fed manually, and have had to be adjusted for the thickness of the material being sanded. As a preliminary to this adjustment, the materials to be treated have had to be graded for thickness.

I have found that it is possible to feed a sanding machine automatically without change of adjustments, and to have it adapted to all kinds, shapes, and sizes of materials.

It is therefore an object of this invention to provide a sanding machine of general application for the sanding of all kinds, shapes, and sizes of materials.

It is a particular object to produce a sanding machine which is especially adapted for the sanding of leather taps and strips.

It is another object to permit the handling of pieces of leather which vary in uniformity of thickness and shape.

It is also an object to provide means for altering the depth of the sanding cut.

It is an additional object to perform the sanding operation automatically and without the necessity of changing the adjustment of the machine on account of variations in the thickness and shape of the materials being sanded.

With the above and other objects in view, which will be apparent as the description proceeds, I have set forth my invention in the following specification and have illustrated it in the accompanying drawings, in which:

Figure 1 is a side elevation of my sanding machine with certain parts broken away for the sake of clarity;

Fig. 2 is a plan view thereof;

Fig. 3 is an end elevation, partly in section on the line 3—3 of Fig. 1;

Fig. 4 is a plan view with the main conveyor mechanism and certain other parts removed;

Fig. 5 is an enlarged longitudinal sectional view on the line 5—5 of Fig. 7, showing the feed-in mechanism and the first sanding drum;

Fig. 6 is an enlarged plan view of the cross-head advancing a tap;

Fig. 7 is a greatly enlarged transverse section on the line 7—7 of Fig. 1; and

Fig. 8 is an enlarged transverse section on the line 8—8 of Fig. 1 with the lower portion broken away.

In the accompanying drawings, I have illustrated the preferred embodiment of my invention

and have shown it in connection with a machine for sanding leather taps and strips, but it will be apparent that it is not limited thereto, and that it is of general application for sanding all kinds, shapes, and sizes of materials.

In its broadest aspect, my improved sanding machine is adapted to have the materials which it is desired to sand supplied to a hopper, automatically fed, one at a time, to the conveyor mechanism, propelled progressively through the sanding mechanism while being held in contact therewith, then to a brush, and finally ejected from the machine onto any convenient support or receptacle.

It will therefore be convenient to explain my new sanding machine by referring to the following sub-divisions, which will be explained in the order named:

- A. Feed-in mechanism
- B. Conveyor mechanism
- C. Sanding mechanism
- D. Operation
- E. Modifications

25 A. Feed-in mechanism

A plurality of taps 10 are stacked in a hopper 11, supported by a plurality of vertical rods 12, as best shown in Figs. 1 and 5. The taps are fed

30 by gravity into the path of a reciprocating cross-head 13 when the latter is retracted, as explained below, and are advanced between a spring-tensioned pressure roll 14 and conveyor belts 15.

The latter, of which there are preferably three, 35 arranged side by side, are driven by a spur gear 16 and guided by a plurality of sheaved pulleys 17, 18, and 20, carried by stub shafts 21, 22, and 23, respectively, mounted in the longitudinal frame 24 of the machine. The top portion 25 of the latter is preferably cut away for a short distance at 26 to enable conveyor belts 15 to support taps 10.

Pulleys 17, 18, and 20 are driven by spur gear 16, mounted on stub shaft 23, which meshes with 45 and is, in turn, driven by another spur gear 28 on a countershaft 30. The latter is provided with a sprocket 29 through which it is driven by a chain 31 from another sprocket 32, on a counter-shaft 33, through a small motor, such as a $\frac{1}{4}$ horsepower motor (not shown).

Countershaft 30 is provided with another sprocket 34 which drives a disc 35, mounted on a countershaft 36, through a chain 37 and a sprocket 38 also carried by countershaft 36.

55 Disc 35 is provided with a cross-head 40 that is

adjustable through a nut 41 and is adapted to be received in and guided by a slot 42 in an arm 43, which is pivoted at 44 to a link 45 pivotally attached to cross-head 13. As disc 35 is rotated, under the influence of chain 37, cross-head 40 moves up and down in slot 42 in arm 43, and swings the latter backward and forward to advance and retract cross-head 13, and at each forward motion advances a tap 10 toward pressure roll 14 and conveyor belts 15.

The reciprocating mechanism just described, except the chain 37 and sprockets 34 and 38, is normally housed within the machine framework 46. Access is obtained thereto through a door 47.

The hopper 11 is provided with a stop 48, comprising a downwardly extending arm 50 and a rearwardly extending arm 51 which is pivoted at 52 to a lug 53 carried by hopper 11. Downwardly extending arm 50 projects into the path of taps 10, below the level at which they are retained by vertical rods 12, and prevents more than one tap from entering the machine at a time. In its lowest position, arm 50 is kept slightly (e. g., $\frac{1}{8}$ ") above the bed of hopper 11 by contact of arm 51 with the pivotal support for pressure roll 14. The taps are successively released as arm 50 is intermittently raised slightly by the lowest tap bearing against the rear curved surface of the bottom of arm 50 (Fig. 5) as cross-head 13 pushes the tap forward.

Two of the vertical rods 12 are also provided with a support block 54. This is arranged a suitable distance above the bed of hopper 11 and projects into the vertical path of taps 10, stacked in hopper 11, to support a portion of the weight of the taps above the block, thus taking the extra weight off the taps below and preventing the marking or scarring of the tap surfaces as they enter the machine.

B. Conveyor mechanism

As taps 10 or 10' are carried forward by conveyor belts 15, they are advanced toward a plurality of platens 60, 61, 62, and 63, and pass along under a series of weight blocks 64 carried by a pair of endless chains 65 through pairs of sprockets 66, 67. The latter are keyed on drive shafts 68, 69, respectively, which are supported in ball bearings 73 (Fig. 7) in the upper framework 74 of the machine.

Drive shaft 68 is provided with a sprocket 70 which is driven through a chain 71 by a sprocket 72, also carried by countershaft 30. Sprockets 66 on drive shaft 68 in turn drive sprockets 67 on drive shaft 69 through the endless chains 65.

The individual weight blocks 64 comprise endless belt treads that are removably secured to chains 65 by thimbles 75, which are preferably tapped into the chains through threaded extensions 76. The weight blocks are provided with parallel slots 77 and 78 in their upper and lower surfaces, respectively, to receive the heads 80 of the thimbles 75 and to straddle sprockets 66, 67. The thimble shanks are made slightly longer than the uncut portions 81 of the weight blocks between the parallel slots 77 and 78 to allow the weight blocks a limited up and down movement.

Weight blocks 64 are also provided with friction imparting pads 82, preferably of rubber, which are secured to the outer surfaces of the weight blocks by metal screws 83, whose heads are countersunk at 84. As best shown in Fig. 7, when chains 65 are driven through sprockets 66, 67, the weight blocks are advanced, and, on the upper

portion of their travel, they are supported by a guide bar 85. As they leave the latter, their weight is transferred to sprockets 66, but as they are advanced further, and pass around the periphery of sprockets 66, gravity causes the weight blocks to drop so that they rest against the heads 80 of thimbles 75. As the weight blocks leave the lower side of the sprockets, the sag of the chains allows rubber pads 82 to come into contact with the tops of taps 10 and, through this frictional contact, with the aid of conveyor belts 15, they are advanced into contact, successively, with platens 60, 61, 62, and 63. After the taps leave conveyor belts 15, the same frictional contact between rubber pads 82 and taps 10 continues to advance them as chains 65 are moved toward sprockets 67.

As best shown in Fig. 1, the subsequent lifting of weight blocks 64, as the latter travel around sprockets 67, releases their contact with taps 10, but each tap is not completely released from its contact with the last weight block until it is fed into the path of ejector rolls 86, 87, which expel the tap and allow it to drop onto a table 88.

Ejector roll 86 is carried by links 100, which are pivoted rearwardly at 101 in the top framework 102 of the machine. Ejector roll 87 is carried on a shaft 103, and is driven through a pulley 104 and belt 105 from a sheaved pulley 106 on a countershaft 107, which will be described later.

As best shown in Fig. 1, the right hand sprockets 67 may be adjusted by bolts 108 to vary the tension on chains 65.

Guides 110 and 111 are provided, as best shown in Fig. 8, to hold weight blocks 64 and their rubber pads 82 off the sanding drums described just below. This is a very important part of the machine, as without this or its equivalent the drums would destroy the tap advancing mechanism in a short time.

C. Sanding mechanism

As best shown in Figs. 3, 4, 5, and 8, the sanding mechanism comprises any suitable number of sanding drums 130, 131, of which two are shown in the preferred embodiment. These drums are mounted on shafts 132, 133 that are rotatably supported in housings 134, 135, and provided with any suitable bearings 136, 137, 138 (see Fig. 8).

The drums are each preferably built up of composite members 140, 141, 142, 143, and include a periphery 144 provided with any suitable sanding medium 145, such as emery paper.

The sanding surface 145 of the drum is arranged in line with the path of the taps as they are advanced, and is of a suitable height to project into the openings formed between platens 60, 61, 62, and 63, thus bringing the sanding surface of the drum into contact with the lower surfaces of taps 10 as they are advanced by weight blocks 64.

Sanding drums 130, 131 are driven through sheaves 150, 151, which are keyed to the shafts 132, 133, respectively, and are in turn driven by continuous belts 152 which pass over both sheaves 150, 151, and thence over a sheave 153 carried by the main drive motor 154, supported on the bed 155 of the machine (see Figs. 1 and 3).

The sanding drums are each given an oscillating movement in a substantially horizontal plane, against the pressure of a coil spring 160 around a fixed bolt 161 in framework 162 (see Fig. 3). This oscillating movement is imparted by means of arms 163, 164 (see Figs. 3 and 8), which are

pivoted to the bottom framework of the machine at 165; and at their upper ends are pivoted at 166 to connecting links 167, whose opposite ends are pivoted at 168 to thrust bearing housings 170. The latter are retained in position by collars 171, which are secured to shafts 132, 133 by tapered pins 172. When arms 163, 164 are oscillated, as explained below, shafts 132, 133 are moved horizontally against the pressure of coil springs 173 interposed between thrust bearing housings 170 and the main drum housings 134, 135 that support the rear ends of shafts 132, 133.

The oscillating motion of arms 163, 164 is imparted to them through connecting links 174, one end of each of which is pivoted to arms 163, 164 at 175 (see Fig. 3). The opposite end of each connecting link 174 engages a cam 176, mounted on a cross-shaft 177. The latter is provided with a pulley 178 through which it is driven by a belt 180 from a drive pulley 181 mounted on a shaft 182 of a reduction gear 183.

The raising or lowering of the sanding drums to make a deeper or shallower cut on the taps is effected through wedges 184 that are mounted between the flat tables of brackets 185, secured to the framework 162 of the machine by bolts 187, and the reversely inclined lower portions of main drum housings 134, 135. The corresponding wedges 184 are maintained in alignment with the main drum housings 134, 135 by keys 186.

Wedges 184 are moved toward and away from framework 162 of the machine through the medium of shafts 188, mounted in said framework and threaded into the forward ends of the wedges at 189. Shafts 188 are adjusted through hand wheels 190. Housings 134, 135 are retained in alignment with brackets 185 through a plurality of bolts 191 provided with adjustment nuts 191' for retaining pressure springs 192.

The height of wedges 184 can be changed through an adjustment plate 186', recessed into bracket 185, by a plurality of adjusting screws 193, 194, 195 (see Fig. 3), that are held in the desired adjustment by lock nuts 196. The wedges are held at the desired height by bolts 187.

A dust retaining housing 197, communicating with a dust exhaust pipe 198, is preferably provided to enclose sanding drums 130, 131, as shown in Figs. 1, 3, 5, and 8.

Access is had to the interior of housing 197, for changing and adjusting the sanding drums, through a door 199, as indicated in Figs. 3 and 8.

After passing over sanding drums 130, 131, the taps 10 are carried into contact with a rotating dusting brush 210, mounted on a shaft 211 that is supported in a pair of bearing plates 212, secured to the framework 162 by bolts 213. The brush 210 may be inserted or removed by removing the bearing plates 212. Brush 210 is rotated through shaft 211, carrying a pulley 214, by a belt 215 that is driven by a pulley 216, mounted on a countershaft 217 driven by main drive motor 154.

D. Operation

It is believed the operation of the machine will be clear from the above description, but to avoid any possibility of misunderstanding, I will briefly summarize the sequence of operations.

Power from any suitable outside source, such as a $\frac{1}{4}$ horsepower motor (not shown), is transmitted to the countershaft 33, and thence to the sprocket 29 on countershaft 30 through the chain 31. Countershaft 30 drives disc 35, mounted on countershaft 36 through chain 37. This causes cross-head 40 to move up and down in slot 42

in arm 43 and oscillates the latter to advance and retract cross-head 13, which in turn advances the lowermost tap 10 in hopper 11 between pressure roll 14 and conveyor belts 15.

The latter, driven by pulleys 17, 18, and 20, which are actuated by spur gear 16 through spur gear 28 on countershaft 30, advances the tap 10 toward the platens 60, 61, 62, 63. In so doing, the tap passes under the series of weight blocks 64 carried by endless chains 65 through sprockets 66, 67. Sprockets 66 are driven by a sprocket 70 through a chain 71 and a sprocket 72 on countershaft 30. Sprockets 66 drive sprockets 67 through endless chains 65.

As weight blocks 64 are driven around sprockets 66, the shanks of thimbles 75 allow the blocks 64 to drop until they contact with a tap 10, the heads 80 of thimbles 75 limiting the downward travel of the weight blocks 64 in the event no tap is beneath them. As weight blocks 64 are lowered, their friction-imparting pads 82 engage the upper surface of a tap 10 and propel it across the platens 60, 61, 62, and 63.

As tap 10 reaches the space between platens 60 and 61, it is engaged by sanding drum 130 which is driven by shaft 132 through sheave 150, belts 152, sheave 153, and main drive motor 154. As explained above, arm 163, controlled by a cam 176, which in turn is driven through pulley 178, belt 180, pulley 181, and shaft 182 from reduction gear 183, gives sanding drum 130 an oscillating back and forth movement in a substantially horizontal plane. This sands the lower surface of the tap the desired amount, and the further travel of the weight blocks 64 advances the tap 10 into the path of sanding drum 131, which gives the tap a similar additional sanding operation.

After still further travel of the tap, effected through weight blocks 64, the tap passes under brush 210, driven by pulley 214 through belt 215 and pulley 216 on countershaft 217 through main drive motor 154. Still further travel of weight blocks 64 propels the tap 10 between ejector rolls 86 and 87. The latter is driven through pulley 104 and belt 105 from pulley 106 on countershaft 107. The weight blocks 64 are then caused to release their pressure from the tap as the weight blocks are propelled around sprockets 67, and the rotation of ejector rolls 86, 87 expels the tap and allows it to drop onto table 88.

This operation is repeated with each succeeding tap 10 as it descends from hopper 11 into the path of reciprocating cross-head 13.

Since the whole sanding mechanism is enclosed in the housing 197, it will be apparent that the dust will collect at the lowest point in the line, namely, in dust exhaust pipe 198, from which it is preferably continuously removed by connecting pipe 198 to any suitable exhaust system.

Although I have referred herein to the taps 10, it will be obvious that my machine is not limited to the use of taps, and, where I have used the term "taps" herein, I mean to include soles, strips, or any other desired flat pieces of leather or of other materials, as my sanding machine is of general application for the sanding of all kinds, shapes, and sizes of materials, although it is particularly adapted for sanding leather articles.

E. Modifications

It will be obvious that any desired number of conveyor belts 15 may be utilized; that where more or less than 2 sanding drums 130, 131 are

desired, the corresponding operating mechanism can be increased or diminished; that the size, shape, and speed of the machine and its various components can be adjusted to the work being handled and the desired rate of production; likewise, the sanding drums 130, 131 can be made of different construction from that illustrated, although the form indicated herein is the preferred form and it is described more fully and claimed in a companion application Serial No. 10 437,071 filed March 31, 1942..

It is apparent that many widely different embodiments of this invention may be made without departing from the spirit and scope thereof, and, therefore, it is not intended to be limited except 15 as indicated in the appended claims.

I claim:

1. In a sanding machine, the combination of a work hopper, a reciprocating mechanism for positively advancing the work units one at a time, 20 sanding mechanism arranged in the path of the work, means for actuating the sanding mechanism, and a continuous conveyor mechanism movable longitudinally of the machine for progressively propelling the work units forward 25 without rotating them, the conveyor mechanism including independently operable vertically movable means for holding the work units in contact with the sanding mechanism.

2. The sanding machine of claim 1, in which the last-mentioned means comprises a plurality of weight blocks carried by endless chains which allow the weight blocks to drop by gravity onto the work units and advance them into and out of the path of the sanding mechanism.

3. In a sanding machine, a conveyor mechanism for the units to be sanded comprising two pairs of sprockets, each pair being mounted on a common shaft, endless chains passing around the sprockets on both shafts, a plurality of weight blocks each secured to both endless chains, and means for permitting the weight blocks to have a limited up and down motion with respect to the endless chains.

4. The conveyor mechanism of claim 3, in which each weight block is secured to the endless chain by thimbles, each of which is provided with a shaft which is longer than the portion of the weight block through which it passes and with a head to limit the downward movement of the weight block.

5. The conveyor mechanism of claim 3, in which longitudinal guides are arranged below the path of the weight blocks to prevent them from dropping below a predetermined level.

6. A weight block for a sanding machine comprising a main body and a friction imparting tread surface of resilient material removably secured thereto, the main body being provided with parallel slots on its under surface and with apertures extending through the weight block in line with said slots to receive means for securing the weight block to adjacent mechanism.

7. In a sanding machine, a hopper in which the work units are stacked in vertical alignment and means for preventing more than a single work unit from being discharged from the hopper at a time, said means comprising a pivoted arm carried by the hopper and overhanging the lower end of the hopper so that the lower portion of the arm extends into the path of the lowest work unit in the hopper, and means for alternately raising and lowering said arm a sufficient amount to permit the discharge of said work units, one at a time.

8. In a sanding machine, a hopper comprising a supporting base, a plurality of vertical retaining rods to confine the work units laterally, and a stop carried by two of said rods and projecting into the path of the work units to carry a portion of the weight of the work units thereabove and prevent scarring of the work units therebelow.

9. In a sanding machine for leather taps, the combination of a hopper in which the taps are stacked vertically, a reciprocating cross-head for advancing the taps one at a time from the hopper to a conveyor mechanism, a plurality of endless belts for receiving the ejected taps, a hold-down roll for the taps in proximity to the endless belts, an endless belt conveyor mechanism to receive the taps from the first-mentioned endless belts and propel them progressively, a sanding drum arranged below the second-mentioned endless belt conveyor mechanism, means for rotating the sanding drum, means associated with the second mentioned endless belt conveyor mechanism to hold the taps in contact with the sanding drum as the taps are advanced into and out of contact therewith, a brush to remove particles of dust, and means for ejecting the taps from the machine.

10. The sanding machine of claim 9, in which means are provided for oscillating the sanding drum in a substantially horizontal plane while it is being rotated around a substantially horizontal axis.

JACK P. ELLIOTT.
